STRAND FEEDING MECHANISM

Herman Staub, Wyomissing, Pa., assignor to Textile Machine Works, Wyomissing, Pa., a corporation of Pennsylvania

Application July 17, 1934, Serial No. 735,615

13 Claims. (Cl. 96—13)

My invention relates to strand or yarn operating devices for textile machines, especially high speed braiding machines and the like, and particularly to means for feeding, guiding and tensioning the yarn, and stopping the machine upon the depletion of a yarn package.

In certain machines, wherein relatively long lengths of the yarn or other strand being fed to the machine extend between the source of strand supply or package, and the strand-working position, these strands are so related to machine parts and to other yarns that, at the completion of unwinding of a strand from its spool, a long section of yarn in slack condition becomes jammed in the machine parts and entangled with other yarns. This condition causes substantial loss in the labor expended in reconditioning the machine, and in the interruption of production, and also, even where serious jamming and entanglement do not occur, the free end of the yarn of the depleted package may, before the machine stops, feed into the machine among the machine parts, out of the thread guides and tensioning means, and away from the loading position or package carrier to a position inaccessible for splicing or tying to the yarn of a renewal package.

One object of my invention is to provide novel and improved strand feeding means to avoid jamming the machine and entangling the yarns, and to stop the machine, upon the depletion of a package, with the yarn thereof still in operative relation to its guides and other machine parts, and an end of the yarn adjacent to the yarn package carrier or loading position accessible for connection to the leading end of the yarn of a renewal package.

In certain types of textile machines, especially high speed rotary braiders, the centrifugal force set up by the relatively high speed of the rotating parts of such machines tends to cause binding or distortion of certain parts of the strand-feeding mechanism, thus resulting in failure of these parts to properly operate under conditions of yarn breakage, depletion of the yarn package and the like.

It is, therefore, another object of the invention to provide strand-feeding means of the aforesaid character which is substantially unaffected in its operation by the centrifugal force acting on the various parts thereof, and in which quick and positive action of the strand feeding means will be assured, notwithstanding the high speeds at which the machine may be operated.

Additional objects of the invention reside in

providing certain novel features of construction and assembly, guiding the yarn from one carrier through the intermediary of another carrier to the fabricating position, facilitating the loading of successive yarn packages to the same carrier, better utilizing an effect obtained by securing the inner end of the yarn of a package to a core thereof, providing and improving the operation of certain parts extending vertically or parallel to the axis of rotation of a horizontally-rotating carrier support, constructing a combined yarn-reserve feed, latch and yarn guide structure as a single piece or wire-like unit, and rendering the device generally an improvement in its field, by causing it to be simple and durable in construction, economical to manufacture, and effective in its operation.

With these and other objects in view, which will become apparent from the following detailed description of the illustrative embodiments of the invention shown in the accompanying drawings, my invention resides in the novel elements of construction, mechanisms and combination of parts in cooperative relationship, as hereinafter more particularly pointed out in the claims.

In the drawings:

Figure 1 is a top plan view of portions of the lower support of a high-speed rotary braiding machine embodying the invention;

Figs. 2 and 3 are views taken in the direction 30 of the arrows 2 and 3, respectively, in Fig. 1; Fig. 3 being enlarged;

Figs. 4 and 5 are views of a portion of the structure of Fig. 3, but on a reduced scale relative thereto, illustrating parts thereof in different operating positions;

Fig. 6 is a view taken substantially along the line 6—6 of Fig. 1, with the yarn package indicated in broken lines;

Fig. 7 is a view taken substantially along the line 7—7 of Fig. 3;

Fig. 8 is a view taken substantially along the line 8—8 of Fig. 1;

Fig. 9 is a view taken substantially along the line 9—9 of Fig. 3;

Figs. 10 and 11 are similar to Fig. 9, illustrating the parts thereof in different operating position;

Fig. 12 is a view similar to a portion of Fig. 3, of a modified form of the invention;

Fig. 13 is a view of a modification of the device shown in Fig. 12, taken as seen by looking in the direction of the arrow 13 in said figure;

Fig. 14 is a view taken substantially along the line 14—14 of Fig. 12; and

Fig. 15 is an enlarged view taken substantially along the line 15—15 of Fig. 12.

The invention is particularly adapted for operation in a high-speed rotary braiding machine 5 wherein the yarn packages are arranged in two annular sets or series, one above or within the other, as the case may be, on supports which rotate in opposite directions, respectively, about the braiding point. The braiding former is adjacent to the upper or inner set, thereby requiring short lengths only of yarn from the packages of such set, and long yarn sections from the lower or outer set of packages to the braiding point.

In connection with the lower carrier support structure of the machine illustrated, each of the long yarn strands, from the package to the braiding point, extends from its spool or bobbin on the lower support, over yarn guides, and is provided with a tensioning device which stops the machine 10 when the yarn breaks or runs off the spool. From the tensioning device, the yarn extends past a plate or templet device for deflecting it laterally in a sinuous path, as it feeds longitudinally, causing 15 it to have interweaving braiding movement 20 relative to the packages and yarns of the upper support.

In pursuing its course, the yarn from each lower carrier extends over and about, and crosses, a great many machine parts, such as bearings, fliers, 30 the yarn guides of the upper support etc., so that, when it breaks or feeds off its package, entanglement and jamming may occur, which occasion considerably greater trouble and expense than when a yarn of an upper carrier breaks or feeds 35 off its spool.

The feeding member herein relating to the longer yarn being vertically disposed, and being differently affected by the centrifugal forces and other operating effects of the machine, means 40 are provided to latch the feeding member of the lower support stopping mechanism by a more positive action and to support the feeding member by the latch whereby the latter may operate effectively in accordance with the new surrounding 45 ing conditions and effects.

Also, in the lower support structure of the present invention, the tension rods and reserve yarn feed elements are of such character and are so actuated along paths transversely to the 50 direction of centrifugal forces of the support as a unit, that unless compensated for, as by the invention, the action of the parts, and of the machine, as a whole would be ineffective, certain of the adverse effects which would be present, if 55 not compensated for in accordance with the invention, being arching or bowing tendencies of the elongated rods and elements, and a binding action between sliding parts transversely to the direction of slide.

60 For the sake of simplicity, only those parts of a rotary braider necessary to an understanding of the invention are shown, the various other parts and their manner of operation being well known in the art.

65 Referring to Fig. 1, a main lower deck support or base 20 journaled on, and rotatable about, a vertical standard 21, supports about the perimeter thereof, an annular series of spaced brackets 23, two of which are shown. Each bracket 23 70 comprises a main body or arm portion 24 extending substantially radially in a horizontal plane, from an inner end portion or base 26 that is secured to the rotary base 20, as by bolts 27. The portion 24 has horizontal outer and inner side 75 arms 29 and 30, respectively, extending in the

direction of rotation, as indicated by the arrow A. At the outer end of the arms 29, a pivot pin 32 is provided for one end of a spindle 33, the other end of which is normally held by a detent member 35. The latter is pivoted, as by a pin 31, to the arm 30 and normally biased to latching position by a leaf spring 38 that is suitably secured to the base 26 as by a screw 39.

Bosses 49 and 41, Fig. 1, at the top side of the body 24, pivotally support therebetween a shaft 10 43, on which are mounted an arm 45, a spring 46 and a nut 47. The nut 47 has notches 49 for engagement with a lug 50 on the boss 40 to adjust the torsional tension of the spring 46 between the nut 47 and the brake arm 45, which normally engages a yarn package 52 on the spindle 33, as a damper or steadyng means to prevent loose uncontrolled rotation of the package, and is limited in its biased direction by a stop lug 53 on the arm 24.

As shown in Fig. 6, the spindle 33 comprises an inner core or rod 54 having a pivot end portion 55, a thrust bearing portion 56 and an opposite end portion 58 for the reception of a nut 59 having a stud-like projection or latch portion 60 for cooperation with the detent member 35. Ball race thrust bearings 62 and 63 surround the rod 54 having enlarged heads oppositely facing against the bearing 56 and the nut 59, and are positioned by a spacer tube 66. Ball race members or sleeves 67 and 68, for cooperation with balls 69 and the bearings 62 and 63, respectively, surround the rod 54 and have annular outer-surface grooves into which correspondingly-grooved portions 71 and 72 of a sheet-metal outer sleeve 73 are pressed, the latter resting, at one end, against a washer-like disc 75 disposed around a portion of the rod 54 between the pivot portion 55 and the thrust bearing portion 56.

Referring to Figs. 1, 2, 3 and 9 to 11, each bracket 23 is provided, adjacent to its outer end, with a vertical standard 77 having a short section below the arm 29 that is bifurcated at 77a to receive a detent member 78 on a pivot pin 79, which pin is surrounded by a spring 80 and a spring-adjusting nut 81 for controlling the movement of the detent member about its pivot. The detent member 78 has a notch portion 83 and a portion 84 projecting therefrom for engagement with a usual stop motion lever 86, Fig. 11, of the braiding machine.

In the standard 77 is a groove or slideway 88, which, in this form of the invention, is of rectangular cross section, for the reception of a rod or element 90 of like cross section filling the groove with a smooth machine fit. The rod 90, carrying at its lower end, a combined thread guide and latch member 92, in the form of a headed pin projecting therefrom, is retained laterally in the groove, as by a sheet-metal angle plate 93 and screws 94, and is limited in its downward movement by a screw 95 disposed vertically in the top end of the rod and having its head larger in diameter than the groove for engagement with the standard. The latch member 92 is normally held by the detent 78 against the notch 83 of the latter, as in Figs. 2, 3, 9 and 10.

A vertical tension rod 96 is supported in laterally-projecting bearing portions 97 and 98, on the upper and lower sections, respectively, of the standard 77, these bearing portions 97 and 98 being preferably provided with hardened wearing sleeves 99 and 100, respectively. A helical spring 102 surrounds the tension rod 96 between the upper bearing 97 and a cotter pin 103, or like de-

vice, on the rod to bias the latter downwardly. The rod 96 carries a guide or element 104 at its upper end by which the rod is normally suspended above its lowermost position from a stationary guide 105 on the standard 77 against the action of the spring 102, by a yarn 106 from the yarn package 52 of the bracket following the bracket on which the rod is disposed, this arrangement of the yarn being clearly illustrated in Fig. 1, wherein the yarn 106 extends from the package 52, at the upper part of the figure, to a stationary guide eye 107 on the bracket preceding in the direction of rotation indicated by the arrow A, thence downwardly, see Fig. 3, to and around the combined latch and yarn guide 92, from the guide 92 upwardly to the guide 105 and from the guide 104 to a rod 109, see Fig. 1, on the bracket from which the yarn started. Passing around this rod 109, the yarn proceeds along a section 110 thereof toward the braiding point, in doing which it passes through a sinuous guide slot, between fliers, and through and adjacent to other parts, not shown. This yarn therefore travels a very much greater distance from the package to the braiding former than does a yarn from an upper carrier, and in so doing passes over and about a considerably greater number and complication of parts such that breakage thereof, or the running of the inner end length off the bobbin into the machine, are more likely to result in serious trouble and delay.

The latter objection is prevented by the insertion into the length of yarn, from the package to the braiding former, an extra length or reserve supply B, Fig. 3, made up of a section c extending from the guide eye 107 to the combined latch and guide 92, and of a section d extending from the guide 92 to the top guide or suspension element 104 on the tension rod 96. With this arrangement, when the braiding proceeds to the end of a package to which the inner end of a yarn is tied, the entire pull of the yarn is extended between the yarn feeding into the braid at the braiding former and the then stationary end of the yarn on the bobbin spindle, thus tending to first straighten the yarn free from all bends preparatory to breaking it, if the machine is not stopped in time. The machine, however, is stopped before breaking the yarn, by the action tending to straighten out the loop or bend formed by the yarn sections c and d, which tendency trips the latch 92 from the detent 78, thus freeing the extra length of yarn for feeding to the machine while the portion 84 of the detent moves into the path of the stop-motion lever 86 and the machine is stopped, Fig. 11.

As seen in Figs. 4 and 10, the machine is stopped in response to breakage of the yarn by the tension rod 96 which is thereby dropped from the suspension guide 105 to engage the stop-motion lever 86.

In the above-described structure, as better illustrated by Figs. 1, 3, 4 and 5, the elongated standard 77, the rod 90 and the rod 96 are disposed at right angles to the radial centrifugal forces which therefore tend to arch or bow these members. The standard 77 is constructed to be inherently of sufficient strength to sufficiently resist such bowing but, since the permissible cross-sectional areas of the rods 90 and 96 are more or less limited, the bowing tendency thereof is compensated for in other ways. In the case of the tension rod 96, the bowing is sufficiently prevented by proportioning the lengths of the bearings 97 and 98 along the rod and the spacing thereof relative

to each other along the rod in accordance with the material and the cross-section of the rod. Since this rod is subject to more or less continuous longitudinal reciprocation during operation, to delicately adjust the yarn tension, it is desirable to compensate for the above-mentioned bowing tendency, but not in the manner in which this is done with the rod 83. Since the latter operates only when the thread runs off a bobbin, and is thereby subjected to a strong actuating force, equal to the tensile strength of the yarn, it may be, as shown, completely encased by the standard 77 on three longitudinal sides, as indicated by the structure providing the guide or slideway 88, in which it is braced throughout its length against bowing, in the normally latched position thereof, with its exposed side farther removed from the axis about which the carrier revolves.

In view of the more or less constant reciprocation of the tension rod 96, in effecting delicate adjustments of the yarn tension, the bearings 97 and 98 are further constructed to reduce friction on the rod by the structure of the bearing sleeves 99 and 100. As better seen in Fig. 15, which shows cross sections of the bearing 97 and the sleeve 99, the bore of the sleeve is constructed of substantially greater diameter than the diameter of the rod 96 such that, as the rod is thrown by the considerable centrifugal force set up by the speed of rotation of the machine against the sleeve 99, the rod engages the sleeve over a substantially minimum area thereof commensurate with the maximum clearance which it is feasible to have between the sleeve bore and the rod. In other words, an arc of the cross-sectional perimeter of the rod so impinges an arc of the cross-sectional perimeter of the sleeve as to approach point contact therewith, as at a position E, on the centrifugal line of force represented by an arrow F, shown also in Fig. 1, to thereby cause the rod to approach vertical line contact with the sleeve through such point between the arcs. This is in contradistinction to the usual relation between a reciprocable cylindrical rod and its cylindrical bearing or journal in which the latter engages the bearing substantially entirely around the rod, with a close sliding fit. The construction of the invention in this feature also prevents sticking of the rod to the bearing from lubricant which becomes gummy from inactivity of the machine. The sleeve 100 of the lower bearing 98 is constructed similarly to the sleeve 99, as illustrated in Fig. 15, and similarly cooperates with the rod 96.

In the form of the invention illustrated in Figs. 12, 13 and 14, in which corresponding parts are designated by corresponding reference characters, the only variation from the above-described structure resides in a modification of the rod 90 of the previous figures, and of the associated parts in the standard. In this modification, in the place of the groove 88 which embraces the rod 90, there is a ridge 88a which is embraced by a rod or plunger 90a in the form of a wire of inverted U-shape having long and short legs 115 and 116, respectively, disposed in grooves 117 and 118. The groove 117 is of substantially channel section, whereas the groove 118 is of the rabbet type. A plate 93a, corresponding to the angle plate 93 of the previous figures, is secured in position, as by screws 94a which extend into tapped openings in the ridge 88a to hold the rod or plunger 90a in relatively free vertically reciprocable position on the ridge 88a.

The longer leg 115 of the plunger 90a is provided, adjacent to its lower end, with a bend which, altho of more or less complex form, is easy to provide. It forms this end to have a latch portion 120, for cooperation with a detent 78a, and a yarn-guide or eyelet 121 for cooperation with the yarn 106, this detent also having a notch portion 83a for the latch 120, and a projection 84a for coaction with the machine stop-motion lever. Thus, the rod 90a, the latch 120 and the yarn guide 121 may be all in one unitary integral piece of standard wire, and the laterally-spaced relation of the legs 115 and 116 provides a wide base, of low friction-surface contact with the standard, to prevent turning of the plunger about its vertical axis, and displacement of the latch and yarn-guide portions. In operation, the structure of Figs. 12, 13 and 14 is practically the same as that above described.

Of course, the improvements specifically shown and described, by which I obtain the above results, can be changed and modified in various ways without departing from the scope of the invention herein disclosed and hereinafter claimed.

I claim:

1. In a device, for a high speed rotary braiding machine including upper and lower oppositely rotatable package supports in which yarn from the lower support is laterally moved sinuously under and over alternate packages on the upper support as the yarn is fed to the braiding point, the combination with an element for stopping the machine, of means including a device for maintaining a reserve supply of yarn between a package on said lower support and the braiding point, and a member for engagement by the yarn to be moved thereby when the yarn tension exceeds a predetermined value to actuate the stopping element and to release the reserve supply of strand to feed the same to the machine until the latter stops.

2. A braiding carrier for a high speed rotary braiding machine comprising a rotary element, a bearing support carried by, and radially offset from the axis of rotation of, said element and having a journal aperture substantially parallel to said element axis, a yarn tension rod longitudinally reciprocable in said journal aperture, the centrifugal force of the rotary element tending to bind the rod laterally against the bearing support in the journal aperture with a force opposing the yarn tension force, and means, for compensating for said opposing force, wherein the peripheral contour of the rod is sufficiently smaller than the peripheral contour of the journal aperture to reduce the peripheral contact between the rod and the bearing support thereby to effect free sliding coaction between the rod and its said bearing support.

3. In a braiding machine, the combination including an element for stopping the machine, a plurality of spaced yarn supports and means including a member mounted on one of said supports for cooperation with a yarn on another of said supports, said means being responsive to predetermined tension in the cooperating yarn for operating said element to stop the machine and to move said member in a direction to cause feed of a reserve supply of yarn to the machine until the machine stops.

4. A strand carrier, for a braiding machine including a high-speed rotatable support, comprising a bearing means for carriage by the support including a cylindrical bore parallel to, and radi-

ally offset from, the axis of rotation of the support, a tension rod supported by said means and having a cylindrical journal in said bore for axial reciprocation relative thereto in response to relatively delicate variations of strand tension, the radial forces of the support caused by rotation thereof forcing the journal transversely against the bore surface to tend to frictionally bind it against said surface to retard its strand-tensioning reciprocation, the bearing bore being of sufficiently greater circumference than the circumference of the journal to reduce contact between the journal and the bore surface to substantially a minimum.

5. In combination, a support, a machine-stopping member, a bracket on the support including a vertical standard, a vertically slidable member on the standard including a strand-guide portion, a latch carried by the standard normally holding the slidable member, the latch being responsive to excessive tension in the strand for release from the slidable member to actuate the machine-stopping member and to release the slidable member to move vertically to feed a reserve supply of strand to the machine until the machine stops.

6. In a braiding machine, means for feeding yarn from a source of supply to the braiding point, an element for stopping the machine, and means including a latch and a member supported by the latch and engaged by the yarn for release from the latch when the yarn exceeds a predetermined tension, said release causing the latch to actuate said element to stop the machine and the member to move in a direction to feed a reserve supply of yarn to the braiding point until the machine stops.

7. In a device for a high-speed rotary braiding machine including upper and lower oppositely rotating package-supports, the combination with the lower support comprising a member for stopping the machine, a peripheral series of spaced brackets on said support and each having a vertical standard, a vertically slidable member on the standard including a yarn-guide portion, a latch carried by the standard normally holding said slidable member, said latch being responsive to excessive tension in the yarn for release from the sliding member to actuate said stop member and to release the sliding member to move vertically to feed a reserve supply of yarn to the 50 braiding point until the machine stops.

8. In a high-speed rotary braiding machine embodying upper and lower package-supports oppositely rotatable in horizontal planes, and a member for stopping the machine, the combination, in the lower support, comprising a main base, a series of brackets spaced peripherally thereon each having side arms for supporting a spindle and a vertical standard, the vertical standard having laterally offset vertical slide-ways and supporting a plurality of yarn guides for yarn from another bracket, a tension rod supported in one of said slideways having a top hook and a bottom operating portion for said stop member, a vertical slide element in another of said slideways having a guide for said yarn and a bottom latch portion, and a latch pivoted to the standard normally holding, and held by, said slide element but responsive to excessive tension in said yarn to be released by said slide element to operate said stop member and to release said element to cause feed of said yarn until the machine stops.

9. In a braiding machine or the like, means for feeding yarn from a yarn package to the braiding

point, an element for stopping the machine, and means including an elongated guide support having laterally-spaced longitudinal slideways and a member of substantially U-shape having its 5 legs on said slideways embracing a portion of the guide support therebetween, said member being engaged by the yarn and movable thereby to actuate said stop element and to feed yarn until the machine stops.

10 10. Carrier structure for feeding a strand from a source of supply to a braiding machine or the like, comprising a yarn support, means for feeding yarn from the support to a yarn-working position, means for stopping the machine, an 15 elongated upright guide support including upper and lower bearing portions and a slideway laterally of said bearing portions, a yarn guide adjacent to the stop of said guide support, an upright tension rod in said upper and lower bearing portions having a yarn guide adjacent to its upper end and a portion adjacent to its lower end for actuating said stopping means, a latch member on said guide support adjacent to the lower end thereof having a portion for actuating 20 said stopping means, and an elongated member 25 on said slideway having a yarn guide portion and a cooperating latch portion adjacent to its lower end.

11. Carrier structure for feeding a strand from 30 a source of supply to a braiding machine or the like, comprising a yarn support, means for feeding yarn from the support to the yarn-working position, means for stopping the machine, a yarn tensioning element having a portion for actuating 35 said stopping means, a latch mounted on said support having a portion for actuating said stopping means, and a member normally held by said

latch and cooperating with said tension element in response to excessive tension in the yarn for release from the latch and movement in a direction to cause feed of a reserve supply of yarn to said mechanism until the mechanism stops, said member being formed as a single-piece wire-like unit bent to form a thread guide and a cooperating latch portion for said latch.

12. Carrier structure for feeding a strand from a source of supply to a braiding machine or the like, comprising a support having parallel slideways, a latch normally mounted on the support, and a member formed as a single-piece wire-like unit bent to form parallel lengths for position on said slideways and having a yarn-guide eyelet 15 and a portion for cooperation with said latch.

13. In a high-speed rotary braiding machine, the combination with a support rotatable about a vertical axis, of a standard on the support radially offset from the vertical axis of rotation thereof, and a vertical cylindrical tension rod journaled near its ends in cylindrical bores of bearings on the standard for vertical reciprocation relative to the standard in response to relatively delicate changes of tension in the strand, the centrifugal forces of the support forcing the tension rod transversely to its length against its bearings on the standard to tend to frictionally bind it against the bearings to retard its strand-tensioning reciprocation, the forces also tending to cause the rod to arch between its journals, the bearing bores being of greater circumference than the circumference of the rod to reduce contact between the journals and the bearings to substantially a minimum, and the bearings cooperating 35 with the rod to prevent arching thereof.

HERMAN STAUB.
